UNITED STATES PATENT OFFICE.

JAMES L. KELLOGG, OF NEW YORK, N. Y.

DESIGN FOR A PENCIL-SHARPENER.

SPECIFICATION forming part of Design No. 32,275, dated February 27, 1900.

Application filed February 5, 1900. Serial No. 4,145. Term of patent 7 years.

To all whom it may concern:

Be it known that I, JAMES L. KELLOGG, a citizen of the United States, residing at New York, in the county of New York and State of New York, have invented and produced a new and original Design for a Pencil-Sharpener, of which the following is a specification, reference being had to the accompanying drawings, forming a part thereof, and in which—

Figure 1 is a top view of a pencil-sharpener bearing and incorporating my design. Fig. 2 is a central vertical longitudinal section of same on the dotted line 2 2 of Fig. 1, and Fig. 3 is a front view of same.

The leading feature of my design consists in the form and configuration of the pencil-sharpener, substantially as shown in the drawings.

In the drawings, A designates the pencil-

sharpener as a whole, said sharpener being elongated and of curved form in cross-section. The portion B of the sharpener is on a lower plane than the main body of the sharpener, as indicated in Fig. 2, and said portion B has a sharp inner edge C. The portion B merges into the sides D, and between the portion B and the main body of the sharpener is a recess E.

What I claim is—

The design for a pencil-sharpener, substantially as shown and described.

Signed at New York, in the county and State of New York, this 3d day of February, A. D. 1900.

JAMES L. KELLOGG.
